Primary Examiner — Cynthia Underwood(74) *Attorney, Agent, or Firm* — Andrew Wilford(57) **CLAIM**

The ornamental design for a hook, as shown and described.

DESCRIPTION

FIG. 1 is a right perspective view of the hook constituting the invention;

FIG. 2 is another perspective view of the invention from above;

FIG. 3 is a perspective view of the back of the invention; and, FIG. 4 is a right-side perspective view of the invention, the left side being identical.

The broken lines are included for illustrative purposes only and form no part of the claim.
